UNITED STATES PATENT OFFICE.

CHARLES T. TOPPING, OF DAYTON, OHIO.

DITCH-DIGGING MACHINE.

Application filed April 3, 1926. Serial No. 99,531.

My invention relates to excavating machinery, and more especially to excavators for digging trenches or ditches for pipe lines, drainage tile, sewer lines and the like.

5 One of the objects of my invention is to provide an excavating device which shall be a self-contained unit adapted for use with farm tractors, which shall be of simple, compact and durable mechanical construction, 10 which shall be readily attached or removed to and from the tractor proper, and which shall comprise a minimum number of operating parts that are readily accessible for manipulation by the operator.

15 Another object of my invention is to provide an excavating mechanism adapted to be associated with a tractor which shall be attached to the tractor portion in such manner as to support the tractor and to permit the 20 ready removal or dismembering of the excavating and tractor parts.

Another object of my invention is to provide a combined tractor and excavating device in which the operating parts are severally associated through a transmission system to a common actuating or impelling device.

30 Another object of my invention is to provide an excavating device especially adapted for digging ditches in which the cutting or excavating mechanism is adjustable relative to its supporting frame structure to vary the depth of the excavation.

Another object of my invention is to provide an excavating device which shall operate on the work to be removed in the path of its impelling mechanism, and which shall be provided with means for discharging or diverting the cuttings to either side of the excavating device.

40 Another object of my invention is to provide an excavating device which shall be adapted to excavate ditches or trenches of a wide range of proportions of widths and depths either centrally of its supporting traction structure or in line with one of its traction members, thereby facilitating the cutting of trenches near walls, curbing or other obstructions.

50 It has been heretofore proposed to utilize the common form of farm tractor for excavating work by removing the rear tractor wheels and supporting the tractor on the frame portion of an excavator supported on its own wheeled axle, and it has been suggested to impel the excavating machinery

and to actuate the excavating mechanism by suitable drive connections with the main drive axle of the tractor.

Although such arrangement can be effectively employed in excavating work, it was found that a device of this nature had serious limitations, and numerous difficulties were encountered in its operation. The main difficulties resulted from the inflexibility of the operating parts, there having been no provisions made for adjustment of the excavator member with respect to the work acted upon, nor were there suitable provisions made for speed reductions and relative operating speeds of the excavating mechanism and the impeller parts.

55 My present invention obviates these difficulties in that I provide an excavating device suitable for use with farm tractors, which is especially designed to have a relatively wide range of cutting actions, its mechanical parts being especially designed to provide a rugged, durable mechanical structure of sufficient flexibility to withstand the shock and strain to which the operating parts are subjected. I have further provided a simple transmission system for coupling the power unit of the tractor with the impelling and cutting mechanism to secure the desirable 80 operating speeds and to coordinate the cutting speed of the excavator with the speed of its advance in the direction of the work.

90 In the accompanying drawings constituting a part hereof, and in which like reference characters designate like parts, Fig. 1 is a side elevational view of an excavating device embodying the principles of my invention; Fig. 2 is a front elevational view thereof; Fig. 3 is a rear elevation; Fig. 4 is a rear elevation of a modified form of excavating device, in which the cutting mechanism is disposed to one side of the longitudinal center line of the device; Fig. 5 is an enlarged view of the head end of the boom or cutter bar carrying the excavating implements; Fig. 6 is a corresponding view of the opposite end of said boom; Fig. 7 is a partial plan view of the transmission system connecting the tractor with the excavating mechanism; Fig. 8 is an enlarged detail view in side elevation partially in section of the gear drive for the tractor wheels; Figs. 9 and 10 are the side elevation and plan view, respectively, of an adjusting device for regulating the position of the boom or cutter bar; Figs. 11, 12, 13 and 14 are, respectively, an end, plan, and side

elevational view of a conveyor system utilized in connection with the excavating device; and Fig. 15 is an enlarged view of the cutter chain illustrating its link construction.

5 Referring to Fig. 1 of the drawings, the structure therein illustrated comprises a tractor 1 having its rear wheels removed from its rear axle 2, which is secured by suitable clamping brackets 3 to a pair of side frames 4, 10 that extend to a yoke, Fig. 2. The rear portion of the frames 4 are journaled on an axle 5, carrying traction wheels 6 and a top frame comprising uprights 7, 8 and 9, and longitudinal frame portion 10 is secured to the 15 frames 4 and partially supported on the axle 5 to rigidly hold the frames 4 in proper spaced relation. A pair of vertical frame members 11 are pivoted on the axle 5 and are provided with bearings 12 and 13 for journaling a 20 main drive shaft and jack shaft for actuating the excavating mechanism, as will be hereinafter described.

A pair of supplemental frames or arms 14 are likewise pivoted at their lower ends to 25 permit swinging movement relative to the fixed frame portions of the tractor and the pivotal arms 11, the frames 11 and 14 being maintained in suitable spaced relation by 30 guide wires or cables 15 that are manipulated by a plurality of screw members 16 for the purpose hereinafter set forth.

A boom or cutter carrying frame 17 comprising a pair of steel cast frame portions 18 that are pivotally mounted to the pivotal 35 frames 11, is provided with a relatively large opening 19 to permit the operation of a conveyor 20 which is suspended therein by links 21. The frame members 18 converge to a reduced section which is associated with a pair 40 of channel irons 22 that are reenforced by suitable lattice work not shown. These channels carry a wheel shaft 23 that is journaled in an adjustable bearing 24 having a screw and nut adjusting mechanism 25 for taking 45 up the wear on the bearing, Figs. 1 and 6.

A pair of endless link chains 30 are disposed around sprocket wheels 31 and 32 which are keyed to the shafts 23 and 12, respectively. The chains 30 are maintained in proper tension by idlers 33 and the tension device 34, 50 Fig. 5. A plurality of excavating buckets 35, are provided with detachable cutters 36 which are fastened to the links of the chains 30 and are adapted to traverse the path of the chains. 55 In Fig. 15 I have illustrated more clearly the construction of the chain 30 which is there shown to be restrained by lugs 30' to maintain the links rigid during the cutting action of the cutters 36. The links provided with the 60 lugs 30' are further provided with openings 30'', for attaching cutters 36 if it is desired to operate the cutter chain without the buckets 35. The main drive shaft 12 is geared to the jack shaft 13 which carries a 65 sprocket wheel 38 and is actuated by a drive

chain 39 connected to the main drive gear 40', Fig. 7, of the excavating device.

The conveyor system disposed in the enlarged opening 19, Figs. 11, 12, 13 and 14, of the cutter bar or frame, comprises an extensible frame 40 and 41 having drive rolls or pulleys 42 and 43 journaled in the respective ends thereof, these rolls or pulleys being driven by beveled gear connection 43' with the shaft 44 having a sprocket gear 45 that is chained to a sprocket wheel 46 secured to the end of the jack shaft 13. A plurality of idler rolls 48 are journaled in the frame members 40 and 41, and an endless belt 50 passes over the end pulleys 42 and 43. The conveyor 55 is adjustable by means of a ratchet 51, Fig. 5, which lengthens or shortens a conveyor support to maintain the belt parallel with the cutting plane in accordance with the different positions assumed by the cutter bar. 60 The pivoted frames 11 are the main supporting members for the excavating mechanism as previously explained, and carry the major portion of its load. It is sometimes desirable, when the excavator is not in use, to 65 position the members 11 so that the weight of the excavator does not overhang beyond the rear axle 5. To facilitate adjustment of these vertical frames I have provided a worm 70 winch and a cable drum 52 at the front end 95 of the top frame 10 which is manually operated by a hand wheel 53. A cable 54 is disposed around pulleys 55 carried by the upright frame portion 7 and pulleys 56, Figs. 1 and 3, journaled in the vertical frames 11. 100 The cable winds on the drum 52 thereby raising the pivot arms 11 to a substantially vertical position. Provisions have been made to raise the frame members 11 and the excavating mechanism carried thereby by the 105 power of the drive mechanism, Fig. 1, this being accomplished by passing the cable around a drum 57 having a sprocket gear 58 that is connected by a drive chain 59 to a pinion member 60 secured on the end of a 110 jack shaft 61, shaft 61 being actuated from the main drive or transmission to which it is connected by a chain 62. The pivot frames 14, Figs. 9 and 10 function to alter the cutting 115 position of the excavating mechanism by shortening the connection of the cable 15 with the boom or cutter bar 17 through the worm adjustment 16, or by shortening the angle between the frames 14 and 11, which 120 raises the cutter or excavating mechanism in a vertical direction. The frame 14 is resiliently supported by a cable 15' which passes over the sheave wheel 15'' Fig. 7.

Referring to Fig. 5, a cleaning finger 65 pivoted on the end of lever 66 is actuated by a cam 67 mounted on a shaft 68 for the purpose of cleaning the buckets 35 when they are tilted in passing over the head sprockets 32. The shaft 68 is driven by a belt or chain 69 from the main drive shaft 12 to provide the 130

proper time relation for the vertical movement of the finger 65 with the spacing of the buckets 35.

Referring to Fig. 7 of the drawings, the transmission system comprises a quill 70 carrying sprockets 71 and 40' that is rotatably mounted on an axle 5. The sprocket wheel 71 is connected by a chain 72 to a wheel 73 rotating with a shaft 74, and the latter is provided at its other end with a wheel 75 having a drive connection 76 with the take-off power unit 77 of the tractor. The rear axle housing 78 which is secured in the frame portion 4 has its extending shaft portions 2 provided with sprocket gears 80 and these are connected with chains 81 to sprocket wheels 82 secured on the ends of a shaft 83. A drive shaft 84 is journaled with its axis in parallel alignment with the wheel axle 5 and is provided at its respective ends with gear wheels 85, Figs. 7 and 8 that interact with teeth 86 of the wheels on the axles 5.

Shaft 84 is connected with shafts 74 and 83 through gear trains 87 and 88 which are interchangeable for the purpose of effecting a greater speed reduction when the excavating mechanism is utilized. A pair of pinions 89 may be disengaged from the shaft 84, and pinions 90 may be secured to rotate with the shaft 74, thereby effecting a greater speed reduction between the shafts 74 and 84. The shaft 74 is provided with a clutch 91 for disconnecting the take-off power unit 77 with the transmission. It will be seen that either the excavating mechanism or the impelling gear drive may be actuated from the take-off power unit or the main differential drive of the tractor, thus providing a range of speeds desirable to meet the operating conditions to which the apparatus is subjected.

Referring to Fig. 4 of the drawings, the cutting mechanism is shown mounted in alignment with one of the propelling wheels, this being accomplished by the addition of the frame portion 93 which can readily be assembled to the main frame of the tractor. This adjustment is sometimes desirable where it is necessary to excavate as close as possible to a wall or curb.

The operation of my excavator mechanism is briefly as follows: The transmission system is actuated by the tractor power plant through the power take-off unit and the main differential drives, as explained in connection with Fig. 7. The excavating mechanism including the buckets 35 and their supporting chains 30, is driven from the sprocket 40' on the quill 70 and the several cooperating movable elements, including the transversely disposed conveyor member 19, are actuated by their connections directly or indirectly with the drive shaft 12.

The excavating unit may be adjusted as heretofore explained, by the hand winch 52 or the power hoist and the depth of the cut-

ting action of the buckets 35 can be regulated by the vertical or pivotal adjustment of the cutter boom or frame with respect to its pivotal support around the shaft 12.

It is evident from the foregoing description of my invention that an excavating device made in accordance therewith provides a simple, relatively inexpensive and durable apparatus, serviceable for excavating ditches, trenches and the like in an economical manner. It is further obvious that it is advantageous to design the excavating mechanism to be adapted for use with a tractor which may be generally employed for farm work when not associated with the excavating mechanism.

Although I have described a specific embodiment of my invention, it will be obvious to those skilled in the art that various modifications may be made in the details of construction and in the design and arrangement of the several cooperating parts without departing from the principles herein set forth.

I claim:

1. An excavator comprising a plurality of side frames journaled upon a plurality of wheeled axles, an overhead frame portion rigidly secured to the front and rear of said side frames, a plurality of pivot arms mounted on one of said axles, a cutter frame pivotally mounted on one of said arms, cutting mechanism mounted on said frame, and means for moving said cutter frame about its pivot support.

2. An excavator comprising a plurality of side frames journaled upon a plurality of wheeled axles, an overhead frame portion rigidly secured to the front and rear of said side frames, a plurality of pivot arms mounted on one of said axles, a cutter frame pivotally mounted on one of said arms, sprocket wheels journaled in the respective ends of said cutter frame, endless chains having excavating buckets secured thereto connecting said wheels, means for actuating said chains and means for advancing the excavator in the direction of the work.

3. An excavator comprising a plurality of side frames journaled upon a plurality of wheeled axles, an overhead frame portion rigidly secured to the front and rear of said side frames, a plurality of pivot arms mounted on one of said axles, a cutter frame pivotally mounted on one of said arms, drive and guide wheels journaled in adjustable bearings in the respective ends of said cutter frame, a plurality of endless chains disposed around said wheels and cooperatively connecting the same, buckets secured to said chains, cutters detachably mounted on said buckets, means for maintaining said chains under tension, and means for taking up the wear on said bearings.

4. An excavator comprising a plurality of side frames journaled upon a plurality of

wheeled axles, an overhead frame portion rigidly secured to the front and rear of said side frames, a plurality of pivot arms mounted on one of said axles, a cutter frame pivotally mounted on one of said arms, a guide wheel journaled in adjustable bearings in one end of said cutter frame, and a sprocket wheel journaled in the other end of said frame, a plurality of endless chains disposed around said wheels and cooperatively connecting the same, excavating buckets secured to said chains, a conveyor mounted in a transverse opening provided in said cutter frame in cooperative alignment with said buckets, and means for cleaning said buckets in the path of said conveyor.

5. An excavator comprising a plurality of side frames journaled upon a plurality of wheeled axles, an overhead frame portion rigidly secured to the front and rear of said side frames, a plurality of pivot arms mounted on one of said axles, a cutter frame pivotally mounted on one of said arms, a guide wheel journaled in adjustable bearings in one end of said cutter frame and a sprocket wheel journaled in the other end of said frame, a plurality of endless chains disposed around said wheels and cooperatively connecting the same, and excavating buckets secured to said chains. 20
25
30

In testimony whereof, I sign my name.
CHARLES T. TOPPING.
